AND COMPANY, LIMITED, OF CROYDON, SURREY, ENGLAND

TELEGRAPH CIRCUITS

Application filed October 20, 1930, Serial No. 489,997, and in Great Britain March 26, 1930.

This invention relates to telegraph systems in which an intermediate repeating station is connected between two terminal stations.

Telegraph systems in which signals are transmitted over a line only in one direction at any one time, are known as simplex telegraph systems. Telegraph systems in which signals may be transmitted simultaneously in opposite directions over a single line without mutual interference are known as duplex telegraph systems.

In simplex telegraph systems in which an intermediate repeating station is connected between two terminal stations it is necessary or desirable to arrange that either of the two latter stations may transmit whilst the other receives. This necessitates switching operations at the intermediate repeating station at each change in the direction of transmission.

In a double current system in which signalling is effected by currents of opposing polarity which is the system in most general use, this is effected by automatic send-receive switches, hereinafter referred to as auto-switches, at the repeating station which are controlled by relays, hereinafter referred to as auto relays inserted in the line circuits in series with retransmitting relays, hereinafter referred to as transmitting relays.

In this case when one terminal station commences to transmit, the signalling current operates the auto relay to one side and the other in response to signalling current from a neutral position. At each extreme position a contact is made which closes the circuit of the auto switch which effects the appropriate switching operation for that direction of transmission. The auto switches are slow to release, are thereby maintained operated during the transit periods of the tongue of the auto relay.

According to the present invention, in a double current telegraph system in which switch means are required to be actuated to an operated position by signalling currents received over a line, means is provided to rectify the signalling currents in order to actuate the said switch means by unidirectional current.

The main advantage of this arrangement is

that the tongue of the auto relay closes the local circuit through the auto switch as soon as the terminal station sends a spacing current preparatory to transmitting, and the tongue is firmly maintained on the operated contact 55 during signalling. It is usual to insert a shunted capacity at the receiving end of telegraph lines to improve the speed of working by minimizing the effect of self induction of the receiving apparatus. In the present invention, the effect of this shunted capacity 60 in series with the rectifier and the transmitting relay is to increase the uni-directional holding current in the auto relay during signalling reversals to an extent dependent on 65 the relative values of the capacity and resistance and the electrical characteristics of the remainder of the line circuit. The distinguishing feature of the invention is that the contact on the auto relay is now firmly 70 maintained at high signalling speeds, whereas previously the duration of contact of the tongue with the limiting contact stops was considerably reduced by the transit time and contact bounce period which increases with 75 the speed of signalling. Further and consequent advantages will be apparent such as that due to the reduced tendency to burning of the contacts and wear of the pivots of the relay. 80

The current rectifier may be of any convenient form but is preferably of the bridge type in which dry metal oxide rectifier elements are inserted in the arms of the bridge.

The accompanying figure shows diagrammatically the connections at an intermediate repeating station in a simplex telegraph circuit according to the present invention.

A line 1 from a terminal station (not shown) is connected to the armature of an auto switch 2, the normal or back contact of which is connected through the winding of a transmitting relay 3, a shunted capacity 4, and a bridge rectifier 5 to earth. The contacts of transmitting relay 3 are connected to a split battery of which the junction is earthed, and the tongue to the operated contact of auto switch 6, for the other section 7 of the line. A relay 8 is inserted in the bridge circuit of the rectifier 5 and when op- 100

erated closes the circuit through the winding of auto switch 6, which operates on the current from battery 9. The connections for the other section 7 of the line to the second terminal station (not shown) are similar to those for the first section. Line 7 is normally earthed through the winding of transmitting relay 10, shunted capacity 11 and rectifier 12. Relay 13 in the bridge circuit of rectifier 12 controls auto switch 2 for section 1 of the line, and the tongue of transmitting relay 10 is connected to the operated contact of the auto switch 2 of this section of the line.

Normally both the terminal stations would leave their terminal switches (not shown) to "receive". This in effect earths the two sections of the line through the respective receiving means. Under these circumstances there is no current in either section 1 or 7 of the line and both auto switches 2 and 6 are in a normal or unoperated position so that each section of the line is connected to earth at the repeating station through the respective transmitting relays 3 and 10, shunted capacities 4 and 11, and rectifiers 5 and 12.

When a terminal station, for example the terminal station connected to section 1, desires to transmit, the switch at that terminal station is turned to "send" and a spacing current is, therefore, put on the line. At the repeating station relay 8 thereupon operates and closes the circuit of auto switch 6 which operates and connects the tongue of transmitting relay 3 to the second section 7 to the line.

The transmitting relay 3 responds to signalling currents over section 1 of the line and the relayed signals are retransmitted over the second section 7 to the second terminal station. During signalling, as previously explained, the reversals of signalling currents are rectified by rectifier 5 and maintains relay 8 in an operated position, due to the effect of the shunted capacity 4 in series in the line circuit, the holding current through the relay 8 is even increased during periods of signalling compared with the steady spacing current during pauses.

It will be seen that this method of controlling of the auto switch by auto relays which are operated by rectified signalling currents provides switching means of a very robust nature compared with the methods previously known.

It will be understood that the actual connections at a simplex repeating station need not be precisely as shown in the accompanying drawing. The general arrangements are well known. The invention which it is desired to protect resides in the manner of control of the auto switches and is defined in the following claims.

What is claimed is:

1. In a double current telegraph system, a line circuit, switch means actuated to an operated position by signalling currents received

over said line, means to rectify said signalling currents to actuate said switch means by unidirectional current and hold said switching means actuated during reception of signals, and a retransmitting relay responsive to signals received over the line circuit to repeat signals into a line controlled by the actuated switching means.

2. In a double current telegraph system, intermediate repeating apparatus connecting two sections of a line, switch means therein to control the direction of retransmission current, rectifying means inserted in each section of said line to convert signalling currents into unidirectional current, and means responsive to said unidirectional current to control said switch means.

3. In double current simplex telegraph repeating apparatus, a bridge rectifier, a shunted capacity and a winding of a signal retransmitting relay together connected in series in each of two sections of a line, an auto relay connected in the bridge circuit of said rectifier and actuated to an operated position by signalling currents rectified thereby, and an auto send receive switch controlled by each of said auto relays.

4. In double current simplex telegraph repeating apparatus a metal oxide bridge rectifier connected in a line circuit, an auto relay connected in the bridge circuit of said rectifier and operable by line currents rectified thereby, and an auto send-receive switch controlled by said auto relay.

In witness whereof I hereunto subscribe my name this fourth day of September, 1930.

FREDERICK WILLIAM JARVIS.
